UNITED STATES PATENT OFFICE.

JOHN MCC. LORD, OF KANSAS CITY, MISSOURI.

SPRING-HORSESHOE.

SPECIFICATION forming part of Letters Patent No. 643,662, dated February 20, 1900.

Application filed May 24, 1897. Serial No. 637,823. (No model.)

To all whom it may concern:

Be it known that I, JOHN MCC. LORD, of Kansas City, Missouri, have invented certain new and useful Improvements in Horseshoes, 5 of which the following is a full, clear, and exact description, reference being had to the accompanying drawings, which form a part of this specification.

My invention relates to improvements in 10 horseshoes, having more particular relation to providing a horseshoe that shall relieve the horse from the objectionable and injurious shock incident to travel over paved streets and hard roads; and my invention consists 15 in certain features of novelty hereinafter described, and pointed out in the claims.

Figure I represents an isometric view of a horseshoe provided with my improvements. Fig. II represents a lateral cross-section of 20 the shoe on the line $x-x$ of Fig. I. Fig. III represents a cross-section on the line $y-y$ of Fig. II. Fig. IV represents a view of the toe of the shoe, showing the manner of securing the two parts of the shoe together at that 25 point. Fig. V represents a similar cross-section to Fig. III with the antifriction-rollers omitted. Fig. VI represents a cross-section similar to that shown in Fig. III, showing a modified form of spring. Fig. VII represents 30 a cross-section showing the recess for the spring in the outer portion of the shoe.

Similar numerals represent similar parts throughout the several views.

The shoe is formed in two parts, the outer 35 and inner shoes 1 and 2, the outer shoe being provided with the projecting ears 3, arranged to be received in the recesses 4 in the inner shoe and fastened by the screws 5, the two parts being thereby secured together. In the 40 outer face of the inner shoe are formed the recesses 6—a suitable number on each side and a suitable distance apart—or, as shown in Fig. VII, the recesses 6 may be made in the outer shoe, and instead of a recess for each spring 45 a continuous groove may be formed, this being the preferable construction. In the outer shoe are provided the openings 7, in which are arranged the studs 8, provided with springs 9, arranged to be received in said recess 6 and bear against the outer face of the inner shoe. 10 represents antifriction-rollers arranged in said recess 6 between the

springs and the recess to lessen the friction of the spring upon the face of the recess. Said springs may be secured to said studs, as 55 shown in Fig. III, by engagement in a groove 11 in the stud, or more simply, as shown in Fig. VI, by a screw 12, passing through the spring and into the stud, the latter being the preferable construction. The springs and 60 studs are so arranged that in normal position the stud will protrude a short distance beyond the face of the outer shoe, as shown in dotted lines, and will by the weight of the horse when brought down upon a pavement 65 or hard road be pressed up flush with said face, in such action the elasticity of the spring serving to break and relieve the force and effect of the concussion when the weight of the horse is thrown upon the shoe on such pavement or hard road. 70

Thus is provided a shoe whereby the injurious effect upon a horse traveling over hard pavements and hard roads is entirely obviated and relieved against. Such a shoe is 75 of particular advantage to road horses and trotters which in driving over pavements and hard roads soon become "stove-up" and stiffened and lose their usefulness by reason of the strain upon the joints, bones, and muscles 80 of the legs and shoulders caused by the jar and concussion in bringing their feet down upon the hard surface of the pavement or road, whereas by providing an arrangement of shoe that will yield to the first impact of 85 the foot, and thus break the jar and prevent the concussion when the foot is brought down, the injurious effect is prevented and the usefulness of the horse is prolonged. A further effect of such a shoe will be that the resilient 90 reaction of the spring after compression will tend to lift the weight of the horse much like the action of a spring-board in jumping, greatly assisting the forward motion of the horse and adding to its speed. 95

Having thus fully described my improvements, what I claim as my invention, and desire to secure by Letters Patent, is—

1. A horseshoe consisting of a hoof-plate provided with recesses 4 and 6, a track-plate 100 provided with openings 7 corresponding with said recesses 6 in the hoof-plate, lugs 3 on said track-plate arranged to engage said recesses 4 in the hoof-plate, and spring-studs

arranged in said recesses 6 in the hoof-plate and protruding through said openings 7 in the track-plate, substantially as set forth.

2. A horseshoe consisting of an inner and outer portion, recesses formed in the shoe between said portions, a series of studs arranged in suitable openings in said outer portion, a series of springs connected with said

studs arranged in said recesses, and anti-friction-rollers arranged between said springs 10 and said inner portion; substantially as and for the purpose set forth.

JOHN McC. LORD.
